UNITED STATES PATENT OFFICE.

THURE DAHL, OF NEW YORK, N. Y., ASSIGNOR TO LIGHTOLIER COMPANY, A CORPORATION OF NEW YORK.

DESIGN FOR A LIGHTING-FIXTURE WALL BRACKET.

Application filed September 22, 1927. Serial No. 23,510. Term of patent 3½ years.

To all whom it may concern:

Be it known that I, THURE DAHL, a citizen of the United States, and residing at New York city, in the county of New York and State of New York, have invented a new, original, and ornamental Design for a Lighting-Fixture Wall Bracket, of which the following is a specification, reference being

had to the accompanying drawings, forming part hereof.

The figure is a perspective view of the lighting fixture wall bracket as applied.

I claim:

The ornamental design for a lighting fixture wall bracket as shown.

THURE DAHL.
